UNITED STATES PATENT OFFICE.

JOHN HERZOG, OF SAGINAW, MICHIGAN.

DESIGN FOR A PHONOGRAPH-CABINET.

No. 38,758.

Specification for Design.

Patented Aug. 20, 1907.

Application filed July 12, 1907. Serial No. 383,534. Term of patent 7 years.

To all whom it may concern:

Be it known that I, JOHN HERZOG, a citizen of the United States of America, residing at Saginaw, in the county of Saginaw and State of Michigan, have invented a new, original, and ornamental Design for Phonograph-Cabinets, of which the following is a specification, reference being had to the accompanying drawing, forming a part hereof.

The drawing is a perspective view of a phonograph cabinet, showing my new design.

What I claim is:

The ornamental design for a phonograph cabinet, as shown.

JOHN HERZOG.

Witnesses:

HARRIET ANSCHUTZ,
JOHN KESSEL.
